TUNING CIRCUIT

Bertram Trevor, Riverhead, N. Y., assignor to
Radio Corporation of America, a corporation
of Delaware

Application February 12, 1932, Serial No. 592,532

8 Claims. (Cl. 179—171)

This invention relates to radio signalling systems, and more in particular to a new and novel means for receiving signals.

More in detail, my invention relates to receiving means comprising a plurality of thermionic tubes connected in cascade by tuned circuits so that signals over a band of frequencies may be received. The interconnecting circuits are controlled in general by a plurality of tuning capacitors all connected to a single control means so that the receiver may be tuned over the predetermined range by a single operation. In these receivers known hereinbefore the initial inductance in the input circuit of the first tube is coupled to a source of oscillations, as, for instance, an antenna system, while the output electrode of each thermionic tube is connected in two circuits, one of which comprises a choking inductance and a source of potential, and the other of which includes a stopping capacity and an inductance which is tuned by a variable capacity similar to the capacity tuning the initial inductance in the input circuit of the system. One terminal of each tuned inductance is connected to the control electrode of a succeeding tube, while the other terminal of the inductance is connected to the cathode of a succeeding tube. The input electrodes of all of the following stages are connected to the output of the preceding stage by an arrangement similar to the arrangement just described.

In systems as described briefly above, and known hereinbefore in the prior art, it has been found that, due to the fact that the choking inductance in the output circuit of one stage is in effect in parallel with the tuning inductance of a following stage, whereas the initial inductance, that is, the tuning inductance connected with the input electrodes of the first tube, is not so connected, considerable difficulty has been encountered in ganging the several tuning capacities so that they keep in step over the entire tuning range. Especially is this true where the frequency of the signal received is well below the normal resonance frequency of the choke coil.

40 Normally additional capacities are placed in parallel with the tuning capacities thereby bringing the capacity of all of the ganged condensers to a value such that they track over the frequency range when used with tuning coils of equal inductances. This did not result in satisfactory operation in some cases since the inductance to capacity ratios of the several stages were dissimilar.

55 An object of this invention is to provide a

new and efficient method of and means for permitting ganging of the several tuned circuits.

The above objects are attained by making the tuning inductances following the input circuit of a value higher than the inductance in the input circuit. When the inductances of all but the first stage are increased sufficiently the parallel inductive reactance due to the choke inductance in the plate circuit will lower the effective inductance in the tuned circuit sufficiently to permit all of the condensers in the set to be ganged.

The novel features of my invention have been pointed out with particularity in the claims appended hereto. The nature of my invention and the operation thereof will be understood from the following detailed description thereof and therefrom when read in connection with the drawing, in which the single figure illustrates one embodiment of the present invention. 15

Referring in particular to the drawing, A indicates an aerial system connected through a coupling inductance 2 to ground G. The receiver proper comprises thermionic tubes 4, 6 and 8 connected in cascade as indicated. The control electrode 3 of thermionic tube 4 is connected through tuning inductance L to the cathode 7 of tube 4. The control electrodes 9 and 13 of tubes 6 and 8 respectively are connected through inductances L₁ and L₂ to the cathodes 11 and 15 respectively. Direct current potential is supplied to the anodes 10 and 12 of tubes 4 and 6 respectively through radio frequency choking inductances I, each of which has one terminal connected to its respective anode and its other terminal connected to a positive point on a source of potential indicated at B+ of potential. The potential oscillations at signal frequency relayed in 4 and appearing on 10 are impressed through blocking condensers BC on to the input circuit of tube 6 while the potential oscillations at signal frequency relayed in 6 and appearing on 12 are impressed through blocking condenser BC, on the input circuit of tube 8. Any radio frequencies appearing in inductances I are shunted around the direct current source by shunting capacities C₁. The fila-

rent source by shunting capacities C_1 . The filaments 1, 11 and 15 of thermionic tubes 4, 6 and 8 respectively are connected through resistances R to ground, thereby maintaining an operative biasing potential between the control electrodes 3, 9 and 13 and their respective filaments. Quiet operation of the receiver is insured by the use of an electrostatic screen S interposed between the inductances 2 and L . The inductances L , L_1 and L_2 are each tuned by a similar capacity C . As is well known, it is desirable in practice to have all

of the tuning capacities C operated by a single control 15, as shown. It is present practice to mount said capacities on a single shaft.

In order to gang the condensers successfully 5 it is necessary that the tune of the several circuits vary in proportion to the angular rotation of the ganged capacities. Since the inductances I are in parallel with the inductances L_1 , L_2 the 10 total effective inductance of the tuned circuits L_1C and L_2C is less than the effective inductance in the circuit LC if the inductances L , L_1 , L_2 are of the same value and each capacity C of like 15 value. For obvious reasons it is desirable that the condensers C for each stage be of substantially the same value. In order that the effective inductance in each of the tuned circuits LC , L_1C , etc., be the same over the tuning range applicant makes the electrical values of inductances L_1 , L_2 larger than the inductance of L . In practice 20 the effective choking inductance of I must be maintained sufficient so that the choke coil is resonant at a frequency above the range to be received on the receiver, so that the frequency 25 of the signal received is below the natural resonance of the choke coil; then the choke coil will present an inductive reactance in parallel with the tuned coil.

Assuming that the effective choke coil inductance remains constant and the normal resonant 30 frequency thereof is well above the frequency of operation of the receiver, the size of the inductances used in the various tuning circuits can be readily determined. For example, where inductance L is 1-1/10 microhenry and the choking 35 inductances I to be used are 13 microhenry, then if inductances L_1 and L_2 are made 1.20 microhenry, the resultant effective inductance of L_1 and L_2 in the tuned circuit when in parallel 40 with the inductances I is in each case 1.10 microhenry. This practical application is given merely 45 for purposes of illustration, and is not intended to limit the present invention since obviously the invention applies equally well to circuits to be used on wave bands other than the one of the example.

I claim:

1. A thermionic relay comprising a plurality of thermionic tubes each having anode, cathode and control electrode, means for applying alternating current potentials to said relay comprising an inductance connected between the control electrode and cathode of one of said tubes, means for connecting said tubes in cascade comprising an inductance connected between the 55 anode and cathode of said tube, a third inductance of an inductive value greater than the inductive value of said first named inductance, said third inductance being connected between the control electrode and cathode of another of said tubes, a capacity connecting the control electrode of said last named tube to the anode of said first named tube, tuning capacities of equal value connected in parallel with said first named inductance and with said last named inductance, and a common control for said tuning 60 capacities.

2. Amplifying means comprising, a signal absorption member, a plurality of thermionic tubes, inductive means for applying potentials to be amplified to the input electrodes of one of said tubes, parallel inductances and a series capacity for coupling the output circuit of said tube to the input circuit of a succeeding tube, the effective inductance of said parallel inductances on the input circuit of said last named tube being made 70

equal to the inductance in the input circuit of said first named tube, to permit tuning of said inductances by similar capacities, one or more variable capacities connected in parallel with said first named inductance, one or more variable capacities connected in parallel with one of said last named inductances, and single control means for said capacities. 5

3. A thermionic relay comprising, a plurality of thermionic tubes, each having a plurality of electrodes including control grid, cathode and anode, a tuned circuit including inductance and variable capacity connected between the control grid and cathode of one of said tubes for applying potentials to be relayed thereto, an inductance 10 for applying charging potentials to the anode of said one of said tubes, a tuned circuit including an inductance and a variable capacity in parallel connected between the control grid and cathode of another of said tubes, said last named variable 15 capacity being substantially equal in value to said first named variable capacity, and a coupling capacity connected between the control grid of said last named tube and the anode of said first one of said tubes, the inductance of said last named 20 tuned circuit being greater than the inductance of said first named tuned circuit to compensate the effect of the inductance for applying charging potentials to the anode of said one of said tubes on said last named tuned circuit, whereby 25 said variable capacities may be controlled as a unit to tune said relay to various frequencies within its range. 30

4. A radio relay including a plurality of tubes, a circuit including an inductance and a variable 35 capacity connected between the control grid and cathode of the first of said tubes, circuits for connecting said tubes in cascade including, a separate inductance for charging the anode electrode of each of said tubes, a capacity connecting the 40 anode of each of said tubes to the control grid of the following tube, and a circuit including an inductance and variable capacity equal in value to said first named variable capacity connected between the control grid and cathode of said tubes 45 following the first, said last named inductance being of greater electrical value than said first named inductance to compensate the effect of said second named inductance on said second named tuned circuit, whereby said capacities may 50 be controlled as a unit.

5. A radio relay as recited in claim 4 in which said second named inductance is normally resonant at a frequency slightly above the highest frequency to be relayed. 55

6. A thermionic relay comprising, a plurality of thermionic tubes, each having anode, cathode and control grid electrodes, means for applying alternating current potentials to be relayed to said relay comprising a tuned inductance connected between the grid and cathode of one of said tubes, an inductance connected between the anode and cathode of said one of said tubes, said inductance being resonant at a frequency above the frequency to which said first named inductance is to be tuned, whereby said inductance presents an inductive reactance to said alternating current to be relayed, and means for connecting said tubes in cascade comprising, a capacity connecting the anode of said one tube to the control 60 grid electrode of another of said tubes, a third inductance connected between the control grid and cathode of said last named tube, said third inductance having an inductive value greater than the inductive value of said first named in- 65 ductance. 70

ductance to compensate the parallel effect of said second and third inductance, whereby said first and third inductance may be tuned by similar capacities operated by a single control.

- 5 7. In an amplifier circuit, at least two electron discharge devices connected in cascade, each of said devices being provided with anode, cathode and grid electrodes, an inductance coil connected between the grid and cathode of the first of said 10 devices, a variable tuning condenser connected across said coil, a source of space current, means including an inductance coil for connecting the anode of said device to said source, a circuit including a capacity for connecting the anode of 15 the first device to a grid of the second device, a tuned input circuit for the second device comprising a connection including an inductance coil between the cathode and said grid electrode thereof and a variable tuning condenser similar 20 to the first named tuning condenser connected across the last named inductance coil, the inductance value of the last named inductance coil differing from the inductance value of the first named inductance coil to compensate for the 25 parallel effect of the second named inductance coil upon the tuned input circuit of the second device.
8. In an amplifier circuit, at least two space discharge devices connected in cascade each of 30 said devices being provided with anode, cathode
- and grid electrodes, a tuned input circuit for the first of said devices comprising a connection including an inductance coil between a grid and cathode thereof, a variable tuning condenser connected across said coil to tune the input circuit to any frequency within a predetermined range of frequencies, a source of space current, means including an inductance coil for connecting the anode of said device to said source, a circuit including a capacity for connecting the anode of 10 the first device to a grid of the second device, a tuned input circuit for the second device comprising a connection including an inductance coil between the cathode and said grid electrode thereof and a variable tuning condenser similar 15 to the first named tuning condenser connected across the last named inductance coil and arranged so as to tune the input circuit of the second device to any frequency within said band of frequencies, uni-control means for said variable 20 condensers for tuning said input circuits simultaneously, said last named inductance coil having a different value of inductance than the first named inductance coil to compensate for the effect of the second named inductance coil upon 25 the tuned input circuit of the second device and an output load connected between the anode and cathode of the second device.
